[57] **CLAIM**

The ornamental design for tweezers for a multipurpose tool, as shown and described.

DESCRIPTION

FIG. 1 is a top front left perspective view of tweezers for a multipurpose tool showing my new design;

FIG. 2 is a left side elevational view thereof;

FIG. 3 is a front elevational view thereof;

FIG. 4 is a right side elevational view thereof;

FIG. 5 is a top plan view thereof; and,

FIG. 6 is a bottom plan view thereof.

In FIG. 3, the broken lines depicting the handle of the multipurpose tool are for illustrative purposes only and form no part of the claimed design.
